CLAIM

The ornamental design for a launcher for a toy glider, as shown and described.

DESCRIPTION

FIG. 1 is a front elevational view of a launcher for a toy glider showing our new design;

FIG. 2 is a right side elevational view thereof, the side opposite being a mirror image;

FIG. 3 is a rear elevational view thereof;

FIG. 4 is a top plan view thereof;

FIG. 5 is a bottom plan view thereof; and

FIG. 6 is a cross-sectional view thereof taken along line 6—6 in FIG. 1.
